CLAIM

I claim the ornamental design for a grooved round sash weight, as shown and described.

DESCRIPTION

FIG. 1 is a perspective view of a grooved round sash weight showing my new design;

FIG. 2 is a top plan view thereof;

FIG. 3 is a bottom plan view thereof;

FIG. 4 is a first side view thereof;

FIG. 5 is a second side view thereof;

FIG. 6 is a rear view thereof; and,

FIG. 7 is a front view thereof.
